KNIFE HOLDER

Russell Sylvester Thatcher, Flint, Mich., assignor to Living Designs, Grand Blanc, Mich., a partnership

Application June 19, 1948, Serial No. 147,082

Term of patent 3½ years

(Cl. D44—29)

To all whom it may concern:

Be it known that I, Russell Sylvester Thatcher, a citizen of the United States, residing at Flint, in the county of Genesee and State of Michigan, have invented a new, original, and ornamental Design for a Knife Holder, of which the following is a specification, reference being had to the accompanying drawing, forming part thereof.

I claim:

The ornamental design for a knife holder, substantially as shown.

RUSSELL SYLVESTER THATCHER.
